UNITED STATES PATENT OFFICE.

CHARLES M. LONG, OF CHICAGO, ILLINOIS.

TRACK LEVEL.

Application filed August 31, 1922. Serial No. 585,501.

To all whom it may concern:

Be it known that I, CHARLES M. LONG, a citizen of the United States, and a resident of Chicago, in the county of Cook and State 5 of Illinois, have invented a new and useful Improvement in Track Levels, of which the following is a full, clear, and exact description.

My invention relates to improvements in 10 track levels, and it consists in the combinations, constructions, and arrangements herein described and claimed.

An object of my invention is to provide a track level which is adapted to straddle a 15 track, and which has means for indicating the number of inches one of the rails is disposed above the other rail.

A further object of my invention is to provide a device of the character described 20 in which the indicator means is entirely enclosed, except for the indicating pins.

A further object of my invention is to provide a device of the character described in which the reading may be done from 25 either side of the device or from the top thereof.

A further object of my invention is to provide a device of the character described which is sensitive to slight variations in the 30 heights of the rails.

A further object of my invention is to provide a device of the character described which has means for automatically disposing 35 the device at right angles to the rails.

A further object of my invention is to provide a device of the character described which is readily portable.

A further object of my invention is to provide a device of the character described 40 which is simple in construction, durable and efficient for the purpose intended, and which is not likely to easily get out of order.

Other objects and advantages will appear in the following specification, and the novel 45 features of the invention will be particularly pointed out in the appended claim.

My invention is illustrated in the accompanying drawings, forming part of this application, in which—

50 Figure 1 is a side elevation of the device shown operatively applied to a track,

Figure 2 is a plan view of the device, and

Figure 3 is an enlarged detailed section of a portion of the device.

55 In carrying out my invention, I provide

an elongated frame such as the board 1 which is of the shape shown in Figure 1. It will be noted that the board is widest at its mid point and tapers from this point to the ends of the board so as to provide a 60 frame which is substantially triangular in shape. The length of the board is substantially the same as the distance between the two rails of a track. Iron plates are disposed at the ends of the board and extend a 65 slight distance beyond the board, these plates supporting the board when it is disposed on the rail. The plates 3 and 4 are not likely to wear out very soon and therefore permit the board 1 to be used a relatively long 70 time. The plate 3 has downwardly extending lugs 5 which bear against the inside of the rail 2 and automatically dispose the board 1 at right angles to the rail. The plate 4 is flat and is adapted to rest upon 75 the top of the rail. From this construction it will be apparent that when the board 1 is disposed on the track and the lugs 5 are brought into engagement with the inside of one of the rails, the board 1 is automatically 80 disposed at right angles to the track, whereupon the indicator will accurately show the difference between the levels of the two rails.

The indicating mechanism comprises a 85 weight in the form of a wedge-shaped plate 6 which has pivot pins 7 projecting from the sides thereof, these pins being provided with a knife-like lower edge 8 (see Figure 3) which is supported in a V-shaped notch 9 90 in the top of the board. The plate 6 is wider at its lower end and is adapted to freely swing within an opening 10 in the member 1. In this manner, the plate 6 is protected on all sides, but is still permitted to 95 swing freely within the opening 10. The underside of the board 1 has an arcuate-shaped recess 11 cut therein. A transversely extending block 12 is disposed within the recess 11 so as to provide an arcuate-shaped slot 13 in the board 1. The member 12 projects laterally beyond the sides of the board 1 (see Figure 2) and has scale markings 14 on the upper surface thereof. The upper surface of the block 12 is arcuate-shaped, the center of the surface coinciding with the pivotal point of the plate 6. The plate 6 has indicator pins 15 disposed at its lower end, these pins projecting through the arcuate-shaped slots 13 and moving over the 110

2
scales 14. In this manner, the device may be read from either side or from the top thereof.

From the foregoing description of the 5 various parts of the device, the operation thereof may be readily understood. A plate 16 is secured to the central flat portion 17 of the board 1 and encloses the upper end of the opening 10, whereby the opening is 10 kept free from dust, dirt, and the like. A handle 18 is secured to the plate 16, the center of the handle being directly above the knife edge 7, so that the frame is evenly balanced when the device is being carried, 15 and thus it can be carried easily by one hand.

When using the device, it is placed upon the rails 2 and is positioned so as to cause the lugs 5 to engage with the inner side of one of the rails. In this way the operator 20 knows that the device is at right angles to the rails. If one of the rails is higher than the other rail, the plate 6 will swing about the point 8 and cause the pins 15 to ride over the scales 14 and to indicate the 25 number of inches one rail is above the other. The scales 14 may be graduated in any manner desired so as to permit the operator to instantly know the distance between the heights of the two rails. In case the rails 30 are desired to be made level, the rails are lowered or raised until the pins 15 are at zero on the scales 14. In this manner, the person using the device instantly knows that the two rails are level. In the case of 35 banking the rails, as for instance, around a curve, one rail may be raised above the

other rail to the desired height by merely noting the places the pins 15 indicate upon the scales 14. The construction of the device entirely encloses the indicating mechanism and at the same time permits the device to be readable from either side thereof, or from the top. The device provides a simple means for instantly showing the difference in height between the two rails. 40 The handle 18 permits the device to be readily moved from place to place along the track. The device is extremely simple in construction and operation, and is durable and efficient for the purpose intended. 45 50

I claim:

A track level comprising a frame adapted to straddle the rails of a track, plates carried by the ends of said frame and being adapted to rest on the rails of the track, one of said plates having downwardly extending lugs adapted to abut the inner side of one of said rails, so as to position the frame at right angles to the rails, said frame having an opening therein and a notch in the upper edge thereof, an indicating arm or weight disposed in said opening and having pins disposed in said notch, and a block disposed in said opening and spaced from said frame to provide a slot between the block and the frame, said block extending laterally beyond the sides of the frame and being provided with a scale on its upper surface, and a pin carried by the arm on each side thereof, and arranged to project through the slot above the scale. 55 60 65 70

CHARLES M. LONG.
